UNITED STATES PATENT OFFICE.

ELWOOD SMITH, OF BREWSTER, WASHINGTON.

ANTILOSS DEVICE FOR SCARFPINS AND THE LIKE.

Application filed August 18, 1922. Serial No. 582,704.

To all whom it may concern:

Be it known that I, ELWOOD SMITH, a citizen of the United States, residing at Brewster, in the county of Okanogan and State of Washington, have invented a new and useful Antiloss Device for Scarfpins and the like, of which the following is a specification.

This invention is an improved loss prevention device for scarf pins and the like.

The object of the invention is to produce a very simple device of this character which can be manufactured at an extremely low cost, which will be efficient in use for its purposes and which in no way will be unsightly, inconvenient or bulky in use on delicate fabrics.

One of the features of the invention is that the device consists of a piece of resilient flat metal, or other suitable material, in a substantial S formation and so constructed as to clamp the fabric on the pin, without injury to the fabric, and to entwine itself about the shank of the pin in such fashion as to maintain itself in its adjusted position on the shank.

Other objects and features of the invention will be apparent from the following description read in connection with the accompanying drawings.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which show the embodiments of the invention as at present devised:

Figure 1 is a front elevation of a scarf pin arranged in a scarf and having the invention applied thereto, as can be seen in dotted lines,

Figure 2 is a rear elevation of the scarf pin shown in Figure 1 and illustrating in full lines the invention applied to the pin,

Figure 3 is a side view of the invention applied to a scarf pin looking in the direction of the arrow a in Figure 1,

Figure 4 is a side elevation of a scarf pin with the invention applied looking in the direction of the arrow b of Figure 1,

Figure 5 is a perspective view of the invention, and

Figure 6 is a perspective view of a modified form of the invention.

Referring particularly to the drawings, the anti-loss device of this invention comprises a strip or piece of resilient metal, or other suitable material, having a substantial S or "ogee" formation with its intermediate portions in irregular formation, as clearly shown in Figures 3, 4, and 5, to enable the device to be applied to the pin so as to entwine itself about the shank thereof, as shown in Figures 1 to 4, inclusive, of the drawings. Due to the resilient character of the material from which the device is made, it will frictionally engage about the pin particularly at the points x, y and z and maintain the device on the pin against casual withdrawing, displacement or detachment.

In the form of the invention shown in Figures 1 to 5, inclusive, the upper end of the device is enlarged as at 2 and is provided with a perforation 3 through which the shank of the pin may be extended. In this form of the invention, the device is moved upward on the shank of the pin so that the lateral extending portion c at the shank of the pin, to which the head or ornamentation d of the pin is usually secured, will extend through the perforation 3, as clearly shown in Figures 3 and 4. In this position, the enlargement or end 2 of the anti-loss device provides a clamping head or plate for forcing the fabric of the scarf in close or tight engagement between it and the head of the pin.

In either form of the invention, when the device is once applied in position, as shown, there is no liability of the device becoming loose, and in view of its flat and uncumber-some construction it lies close to the fabric of the scarf and is entirely hidden from view, even when the scarf can be viewed from its side edge, this being true by virtue of the fact that the device is made of very thin material and entwines itself closely around the shank of the pin. The irregular intermediate portions of the device provide, at 4, an outwardly pressed open loop, which facilitates its application to the pin and which accentuates the frictional contact or grip of the device with the pin at the points x, y and z.

In both forms of the invention shown in

the drawing, the ends 5 and 5^a are put under tension when the device is entwined about the pin and, consequently, obtains a tight grip on the shank thereof.

5 In applying the device shown in Figures 1 to 5, inclusive, the shank of the pin is first inserted through the opening 2 and the device is moved upwardly on the shank so that the portion *c* thereof will extend there-
10 through and the head 2 of the device will lie opposite the head of the pin. The de-
vice is then moved so that the portion 4 of
15 the pin will lie opposite one side of the shank and the end 5 will engage and lie
opposite the other side of the shank, when
slightly flexed as clearly shown in the draw-
ings.

To apply the form shown in Figure 6, it
is only necessary that the device be so ar-
20 ranged relative to the shank that the inter-
mediate portion 4 will engage the latter, and
the ends 5^a may be flexed to engage the op-
posite side of the shank, as shown.

This form of the invention may be used
25 with various types of pins and may be ad-
justed on the pin shank as desired.

From the foregoing, it will be seen that
30 the applicant has provided a very simple
and economical anti-loss device which can be
applied with great ease and celerity and
which will become hidden under the fabric
of a scarf and will not be unsightly in use.

What is claimed is:—

1. An anti-loss device comprising a piece
35 of resilient material having its end portions
extending in opposite angular directions and
adapted to have its intermediate portion ap-
plied to engage one side of a pin shank and
its ends to engage about the opposite side
40 of the pin shank.

2. An anti-loss device of the kind de-

scribed comprising a piece of resilient mate-
rial having a substantial ogee formation,
the intermediate portions of said device be-
ing of irregular formation and offset from
45 the line of said ends, whereby the device
can be entwined about the shank of the pin.

3. An anti-loss device of the kind de-
scribed comprising a piece of resilient mate-
rial having a substantial ogee formation,
one end portion of said device having a per-
foration therein extending at right angles
50 to the longitudinal axis of the device to re-
ceive the shank of a scarf pin and to nor-
mally engage the usual lateral extension
55 thereof at the head of the pin while the
remaining portion of the device engages the
shank of the pin.

4. An anti-loss device for pins comprising
a piece of resilient material having its end
portions extending in opposite angular di-
rections, one of said end portions having a
perforation therein through which a pin
shank may extend, said device being adapt-
ed to be entwined about a pin shank with
60 its intermediate portion engaging one sur-
face of the shank and its other end engaging
the opposite surface of the shank.

5. An anti-loss device of the kind de-
scribed comprising a piece of resilient ma-
terial having a substantial ogee formation,
one end portion of said device having a per-
foration therein to receive the shank of a
pin, the intermediate portions of said device
70 being of irregular formation and lying out
of the line of said ends, whereby the device
can be entwined about the shank to friction-
ally engage the latter.

In testimony whereof I have hereunto set
my hand.

ELWOOD SMITH.
